UNITED STATES PATENT OFFICE.

WILLIAM C. POPE, OF PHILADELPHIA, PENNSYLVANIA.

TRANSFER-TICKET.

No. 805,153.

Specification of Letters Patent.

Patented Nov. 21, 1905.

Application filed February 10, 1905. Serial No. 245,131.

To all whom it may concern:

Be it known that I, WILLIAM C. POPE, a citizen of the United States, residing at Philadelphia, in the county of Philadelphia and State 5 of Pennsylvania, have invented new and useful Improvements in Transfer - Tickets, of which the following is a specification.

This invention relates to certain new and useful improvements in transfer-tickets, more 10 particularly in what are termed "time-limit" transfer - tickets for use by street - railways, traction companies, &c., for transferring passengers from the car of one line to the car of another line at a given transfer-point; and the 15 object is to enable the railroad company to make the transfer as quickly as possible and keep absolute check on the conductors and passengers and by this check to be able to ascertain without question whether the transfers 20 have been correctly issued by the conductors and whether used by the passengers according to conditions under which they are issued or whether these conditions have been abused.

25 A further object of the invention is to provide a transfer-ticket which when used can absolutely prove the correctness of any passenger's claim, thereby preventing lawsuits arising out of disputes between the passengers 30 and the railroad company resulting from the privilege of riding on a transfer being denied a passenger by a conductor when, as often happens, a transfer issued for antemeridian is presented for fare for postmeridian, and 35 therefore refused as fare by the conductor.

The transfers in general use to-day are more or less complicated and open to the abuse hereinbefore stated.

In describing the invention in detail reference 40 is had to the accompanying drawings, which form a part of this specification, and wherein is shown the preferred embodiment of the invention; but it is to be understood that changes, variations, and modifications can be 45 resorted to which come within the scope of the claims hereunto appended.

In the drawings, Figure 1 illustrates a front elevation of the preferred form of transfer-ticket constructed in accordance with this invention, and Fig. 2 a modification.

50 Referring to the drawings by reference characters, the transfer - ticket according to this invention consists of a strip of suitable material divided into a body portion 1 and a 55 postmeridian or afternoon coupon 2, detach-

ably connected to one end of the body portion 1. The coupon 2 will be termed the "P. M." coupon, which is an abbreviation of the term "postmeridian," and the coupon 2 is detachably connected to a stub 3. The coupon 60 2 is separated from the body portion by means of a line of suitable perforations or indentations 4, and the coupon 2 is separated from the stub 3 by a line of perforations or indentations 5. The perforations or indentations 4 65 or 5 enable the body portion to be readily separated from the coupon 2 or the coupon 2 readily separated from the stub 3.

The body portion 1 is provided with a column of abbreviations, as at 6, to indicate the 70 months of the year, and also provided with two columns of numerals, as at 7, to indicate the days of the month. Any suitable arrangement for indicating the month of the year or day of the month can be employed, and 75 that illustrated is by way of example. The body portion 1 is also provided with an inscription, as at 8, to indicate the name of the railroad issuing the transfer, and, furthermore, with a suitable designatory inscription, 80 as at 9, for example, instructions to the passenger to explain when and how the transfer-ticket is required to be used. The body portion 1 has a plurality of inscriptions, as at 10, indicating the transfer - points and also provided with the conductor's number, as at 11. Conventional indications for indicating the 85 hour and the fractions thereof are also upon the body portion 1, as at 12 12^a, 12^b 12^c, 12^d 12^e, the fractions being indicated by enlarged figures 90 and in a different color from that of the hours. A column of figures, as at 13, is also provided on the body portion for the even hours without any fractions. The conventional indications 12 12^a, 12^b 12^c, 12^d 12^e and the column 95 of figures 13 constitute a complete time limit and become an antemeridian time limit if the coupon 2 is not issued with the body portion 1 or become a postmeridian time limit if the coupon 2 is issued with and attached to the body portion 1. The body portion of each ticket is correspondingly numbered with the coupon 2, as indicated by the reference characters 15 16, respectively. The transfer-tickets are consecutively numbered. 100 A legend as follows, "If no coupon attached hour punched is A. M. hour," is upon the body portion 1, as at 17. The day of the month is also indicated by an enlarged figure, as at 14.

The coupon 2 is provided with an abbrevia- 110

tion, as at 18, to indicate the name of the railroad and is further provided with the following notice: "Not good if detached. This coupon denotes that the hour punched on body 5 of 101,012 transfer is P. M. hour."

The coupon 2 may be printed of a different color to that of the body portion 1. The printed matter upon the body portion 1 or coupon 2 may be of any style desired, as well 10 as any arrangement. The coupon 2 may also be provided with the conductor's number, as at 11^a.

When the ticket is to be issued, it is punched in the necessary manner, and if the transfer 15 is issued in the forenoon the coupon 2 is detached from the body portion 1, and if the transfer is used in the afternoon the coupon 2 forms a continuation of the body portion, but is detached from the stub 3. Before issuing 20 the transfer the time limit is punched in the proper manner by the conductor.

From the foregoing description it is evident that a transfer-ticket is set up which consists of a body, a single coupon, and a stub, 25 said body bearing a time limit and the coupon a legend to the effect that when the time limit on the body is punched and issued to the passenger when unaccompanied by the coupon it is an antemeridian transfer, but 30 when issued to the passenger accompanied by the coupon its legend denotes that the time limit punched is postmeridian, so that if the body is issued without the coupon attached it can only designate antemeridian transfer, 35 while if issued with coupon attached and punched it can only designate postmeridian transfer and the passenger or unscrupulous employee would have no object in detaching the coupon, as the transfer is dated, and therefore 40 cannot be used for the next morning, the present morning of course being past when postmeridian transfers begin to be issued.

Should a transfer be issued for antemeridian—that is, the body detached without any 45 coupon—and given to the passenger and the passenger tried to use it postmeridian, saying it was issued for postmeridian with the coupon attached, but that the coupon had fallen off or become detached since issued and 50 the coupon lost, the management takes the transfer over which the passenger and conductor have had the dispute, refers to the conductor's number, calls up that conductor, refers to the consecutive or check number on 55 the body of the transfer, and getting the original pad from the conductor (as the transfer-tickets are issued in pad-like form with the stubs secured together) from which this transfer was issued, refers to the duplicate 60 check-number on the coupon, and if it is in the pad from which the transfer was issued it proves conclusively that the transfer was issued antemeridian, no matter what the passenger or conductor may claim. If the stub

is not there, it shows conclusively that the 65 transfer was issued to the passenger with the stub attached, and must therefore be postmeridian.

In the modified form shown in Fig. 2 the transfer-ticket is substantially the same, with 70 the exception that the coupon 2 is provided with the postmeridian time limit, as indicated by the reference character 19, and the body 1 is provided with the antemeridian time limit 20. The legend or inscription 75 on the ticket shown in Fig. 1 is dispensed with in the form of ticket shown in Fig. 2, and the inscription upon the coupon 2 of Fig. 2 is somewhat different from that on the coupon 2 of Fig. 1. For example, the notice or 80 inscription on the coupon 2 of Fig. 2 reads as follows: "P. M. Transfer not good for passage if this coupon 101,012 is detached from body of ticket," as at 21; but this latter notice means substantially the same thing as the 85 notice or inscription on the coupon 2 of Fig. 1; otherwise than that, as stated, the ticket shown in Fig. 2 is substantially the same as that shown in Fig. 1, the same reference characters being applied thereto. The ticket shown 90 in Fig. 2 is used substantially in the same manner as that shown in Fig. 1.

The inscriptions and time limits upon the transfer-tickets illustrated are shown by way of example; but any arrangement of inscriptions, time limits, or other designations suitable for the purpose may be employed.

Having thus fully described my invention, what I claim as new, and desire to secure by Letters Patent, is—

1. A transfer-ticket comprising a body portion and a coupon, said body portion and coupon bearing conventional indications to constitute an antemeridian transfer-ticket when said body portion is used separately and a postmeridian transfer-ticket when used together.

2. A transfer-ticket comprising a body portion and a coupon, said body portion and coupon bearing conventional indications to constitute an antemeridian transfer-ticket when said body portion is used separately and a postmeridian transfer-ticket when used together, said coupon and body portion being correspondingly numbered to constitute a check.

3. A transfer-ticket comprising a body portion and a coupon, said coupon and body portion bearing conventional indications to constitute, respectively, a postmeridian-indicating coupon and an antemeridian-indicating body portion.

4. A transfer-ticket consisting of a body portion and a coupon and further provided with conventional indications to constitute a postmeridian-indicating coupon and an antemeridian-indicating body portion.

5. A transfer-ticket comprising a body por-

tion and a coupon, said coupon and body portion bearing conventional indications to constitute, respectively, a postmeridian-indicating coupon and an antemeridian-indicating body portion, said coupon and body portion correspondingly numbered to constitute a check.

6. A transfer-ticket consisting of a body portion and a coupon and further provided with conventional indications to constitute a postmeridian-indicating coupon and an antemeridian-indicating body portion, said coupon and body portion correspondingly numbered to constitute a check.

7. A transfer-ticket comprising a body portion and a coupon and further provided with conventional indications to constitute an antemeridian transfer-ticket when said body por-

tion is used separately and a postmeridian transfer-ticket when used together.

8. A transfer-ticket comprising a body portion and a coupon and further provided with conventional indications to constitute a complete transfer-ticket for one part of the day when said body portion is used separately and a complete transfer-ticket for another part of the day when said body portion and coupon are used together.

In testimony whereof I have hereunto set my hand in presence of two subscribing witnesses.

WILLIAM C. POPE.
